UNITED STATES PATENT OFFICE.

JOSEPH L. LEVY, OF NEW YORK, N. Y.

METALLIC CAR.

No. 863,615.

Specification of Letters Patent.

Patented Aug. 20, 1907.

Application filed May 18, 1903. Serial No. 157,547.

To all whom it may concern:

Be it known that I, JOSEPH L. LEVY, a citizen of the United States, and a resident of the city of New York, borough of Manhattan, county and State of New York, have invented certain new and useful Improvements in Metallic Cars, of which the following is a specification.

Heretofore it has been customary to form the side sills of such cars of a peculiar and special shape without regard to commercial forms of iron or steel which are readily produced and also kept in stock by the dealers; and so these sills cannot be easily obtained but have to be specially made by expensive machinery, and the car body or hopper is built upon these sills and fixed to them. The buffer bars and end sills are also special and complicated, and are connected to the car body or hopper, by means of braces, so that the frame and hopper are as rigid as possible. These cars are designed to carry large masses of heavy freight, such as coal and iron ore, and so are often found to be very severe on the track and running gear. Whenever these cars are involved in a wreck or similar accident, so that the metal of the car is badly bent or buckled, repairs are difficult because of the size of the parts, their irregularity, and weight, and the complication of the structure.

The object of my invention is to overcome these disadvantages and difficulties by providing a car in which only commercial forms of iron or steel are used which may be readily obtained, and these are so combined that any part may be readily replaced or repaired. The hopper or car body is made lighter than ordinarily, and is braced by a side frame that is preferably spring supported on the main frame, whereby the hopper may easily carry the usual heavy loads without injury to either the track or the running gear. The car body is supported in a "hog back" frame that is spring supported in the main frame and both the hog back frame and a car body springs supported in its frame I regard as entirely and broadly new as will hereinafter appear.

While my invention is more particularly applicable to the type of cars above described, it may be embodied in many other types, to a greater or lesser extent, as the fundamental features of my design are broadly new and of wide application.

For a more particular description of certain embodiments of my invention, reference is to be had to the accompanying drawings forming a part hereof in which

Figure 1 is an elevation of one type of my improved car, the running gear being shown diagrammatically. Fig. 2 is an end elevation of the same, a portion of the frame being broken away. Fig. 3 is a longitudinal section taken on the line 3—3 of Fig. 2 and looking in the direction of the arrows. Figs. 4 and 5 are sections taken on the lines 4—4 and 5—5 of Fig. 1, looking in the direction of the arrows. Fig. 6 is a plan view of the portion of the hopper shown in Fig. 3. Fig. 7 is a plan

view of a portion of the frame, the parts being broken away to more clearly disclose the structure. Figs. 8, 9 and 10 are detailed views showing the bracing and tying means for the car body. Figs. 11 and 12 are sectional views taken on the line 11—11 and 12—12 of Fig. 3, and looking in the direction of the arrows. Figs. 13 and 14 are sectional views of the bolster and a part of the frame. Fig. 15 is a sectional view showing the part of the frame to which the king bolt is secured. Figs. 16, 17 and 18 are views showing portions of the frame and bolster. Fig. 19 is a perspective view of a portion of my improved car.

Similar reference characters designate similar parts throughout the several views.

The trucks 1 form no part of my invention and may be of any suitable type, and are connected to a frame 2 in any suitable way. The frame 2 is composed of the side sills 3 and 4 which may be of any suitable form, although I prefer making them of channel iron 75 with the flanges turned outwardly. At their ends, the sills 3 and 4 are connected by channel irons 5 which are secured to said sills by means of external angle plates 6 and internal angle plates 7 and the side sills 3 and 4 and the end sills 5 are also connected by 80 means of a bar 8. The side sills 3 and 4 are also united by means of I-irons 9 and 10 which are secured to said side sills by means of rivets and angle plates 11. To further strengthen the structure the crossings 9 and 10 are riveted to the sheet metal braces 12 and 13 which 85 pass below each of the side sills and said crossings, and are riveted to said side sills, and the upper surface of said sills, and crossings are united by a second set of sheet metal braces 14 and 14^a to which they are riveted. The outer ends 15 and 16 of the sheet metal braces 14, 90 14^a are bent upwardly as will hereinafter appear. An intermediate plate is also centrally located on said crossings.

The crossings 10 are connected with the adjacent end sills 5 by means of longitudinally disposed channel 95 irons 17 and 18 which are rigidly secured to said crossings 10 and end sills 5 by means of rivets and angles 19. The longitudinally-disposed channel irons 17 and 18 not only brace the structure, but also serve to support the coupling which forms no part of my invention, 100 and is not shown or described in this application. Diagonal braces 20 and 21 connect the crossings 10 and end sills 5 and are riveted to the sheet metal braces 14, 14^a and 8.

As stated above, the ends 15 and 16 of the braces 14 105 are bent upwardly at right angles, and these braces are connected by channel irons 22 and 23 which are riveted to the plates 14 and to angles 24 which rigidly connect them to the ends 15 and 16. These channels serve to reinforce and strengthen the structure and 110 extend over the side sills as indicated in Fig. 18. On each of the plates 14, between the channel irons 22

and 23 are placed spring caps 25. Three of these caps are shown, one at each side, and one in the center, although it is obvious that a greater or lesser number may be employed if so desired. Each of these caps 5 is preferably designed to seat four springs which are designated by the characters 26, and these springs 26 are preferably mounted by caps 27. It is obvious that elliptic springs may be substituted for these coil springs if desired, although for most purposes I find 10 coil springs to be preferable. The caps 27 are fixed to parallel I-beams 28 and 29 which extend over the springs 26 and run parallel to the channel irons 22 and 23, and extend above the same. The upper webs of the I-beams 28 and 29 are united by a channel iron 30, 15 the flanges of which extend downwardly and adjacent to the inner surfaces of the channel irons 22 and 23. These channel irons are connected by the tie-bars 31 which are offset sufficiently to extend above the bolster which is formed by the I-beams 28 and 29, and the channel iron 30, and they are so arranged as not to interfere 20 with this movement. The upper surface of the channel iron 30 is covered with a triangular tube 32 which is riveted to it except at the points over which the straps 31 pass, where the tube 32 is indented at 33, to 25 permit the bolster to move downwardly and compress the springs 26 without disturbing the straps 31. The ends of the tube 32 terminate short of the ends of the channel iron 30 to provide a bearing on which ends of the side frames 34 rest. From the above it is obvious 30 that the I-irons 28 and 29 with the channel iron 30 forms a bolster which is spring supported. Between the crossings 9 and 10 is a centrally located chair 9^a which is riveted to said crossings and is provided with a central bar 9^b through which the king bolt may be 35 passed. The lower surface 9^c of the chair 9^a is shaped to form a center bearing which rests on the truck. The said frames 34 each comprise one straight angle bar 35 with its lower flange outwardly disposed, and ends of said angle bar are united by a curved or hog- 40 back angle bar 36, the flange of which extends outwardly from its upper edge, and at their points of union, the bars 35 and 36 are provided with reinforcing plates 37 to which they are riveted. The said frame 34 is secured to the hopper or car body 38 by rivets and also 45 by angle bars 39 which are riveted to the frames 34, hopper 38, and the tube 32, so that the hopper, side frames and bolsters are resiliently supported in the frame 2 by the springs 26, and the contents of the hopper or car body are carried in such a way that the running gear and track are protected against injury by 50 heavy loads. The side frames 34, tubes 30, and angle bars 39 constitute a secondary frame.

The hopper 38 comprises the usual side walls 40 and 41 which are united by the end walls 42, and inclined 55 bottoms 43 and 44 as well as by tie-rods 45 and channel iron braces 46 which extend from vertically disposed channel irons 47 and 48, which are riveted to the inner walls of the car. Vertical channel irons 49 are also riveted to the inner walls of the sides 40 and 41 and at 60 the medial lines thereof, and these channel irons 49 are united by a tie-bar 50 which is secured to the sides 40 and 41 by means of angle plates 51 and rivets, as clearly shown in Fig. 10. This bar is situated in the same horizontal plane as the angle bars 35, and so is secured 65 rigidly to them.

To further brace the bottoms 43, angle irons 52 and 53 are riveted thereto and running parallel to the angle bar 39 and located on each side thereof about midway between the angle bar 39 and the ends of the bottom. The lower ends of the bottoms 43 are further reinforced 70 by similar angle bars 54 secured in the same way. Angle bars 55 and 56 extend along the upper and outer edges of the sides 40 and 41 and a similar angle bar 57 extends along the upper and outer edges of the ends 42, and to further brace the hopper 38 angle bars 58 75 75 are placed between the sides 40 and 41 and the ends 42 and riveted to said sides and ends, and similar angle bars 59 connect the sides 40 and 41 with the bottom 43.

The channel iron braces 46 are secured to the angle irons 55 and 56 respectively by means of reinforcing 80 plates 60 which are riveted both to the said angle bars and braces.

To further strengthen the structure of the car body, or hopper 38, plates 61, 61^a and 61^b are riveted to the lower and outer edges of the sides 40 and 41 adjacent 85 to the channel irons 47, 48 and 49, and the lower edges of the ends 42 are bent at 62 to overlap a portion of the bottom 43.

Centrally located on the bottom of the hopper 43 extending the length thereof is the brace 63 which 90 comprises a central plate 64 with angles 65 and 66 on each side thereof, and riveted thereto, and also to the bottom 43 and terminating adjacent to the ends 42 and angles 67 and 68 are riveted to the plate 64 and ends 42, and approximately opposite the angle bars 53 the 95 brace 63 is reinforced by the sheet metal covering 69, and plates 64^a, 70 and 71 as well as the braces 72 and 73 and 65^a and 66^a. The cover 69 is riveted to the bottom 43 and also is provided with upturned flanges 74 and 75 which are riveted to the angles 65 and 66 and 100 plates 64. The braces 72, 73 and plates 70 and 71 together with a plate 76 which is sandwiched in between them unite the bottoms 43. One half of this structure is disclosed in Fig. 3, but as the other half is identical therewith, it is unnecessary to show and describe the 105 entire structure.

The cover 69 is provided with projections 77 which are riveted to the bottom 44 and this bottom is also riveted to the crossing 50, and to the supports 78. The bottom is secured to the support 79 which is fixed to 110 the crossing 50, and rests on the angles 72 and 73 and also to the angle plates 80 which are riveted to the walls 40 and 41. A crossing 81 connects the said walls 40 and 41 and runs parallel to the crossing 50, and at the lower edges of the bottom 44. Swing bottoms 82 and 115 83 are pivoted at 84 adjacent to the bottom 44 and these swing bottoms are provided with angle iron flanges 85 which reinforce their outer edges. The lower edges of the bottoms 82 and 83 abut against the lower edges of the bottoms 43 and these swing bottoms 120 are located on each side of the covering 69. The bottoms 44 and 43 are so inclined that the contents of the car will slide towards the intersection of the swing bottoms 82 and 83 with the bottoms 43 so that when the swing bottoms are released, the contents of the car 125 may be dumped. No mechanism is shown for securing the swing bottoms against the bottom 43, but as such mechanism is well known in the art, further description is believed to be unnecessary.

From the above it is apparent that my improved 130

hopper is not only braced at the sides and edges, but it is also strengthened and reinforced by a longitudinally disposed brace that extends the length of the car, so that the metal is disposed in this car where it is most needed and where it will produce its maximum effect.

The hopper is rigidly secured between the side frames and is spring supported over the bolster, and as it is resiliently supported from the main frame, axle-box springs, and may or may not be used in the truck, 10 although it is preferable to use them. Because the hopper is resiliently supported either to move up or down, it may readily be removed from the frames by first removing the straps 31, when the hopper 38 may be lifted bodily and removed for repairs or other purposes, as may be advisable. This is of great advantage 15 in case the car should become involved in a wreck, because the frame and hopper could be separated and any damaged parts could be repaired or renewed at a minimum cost.

20 Although the car is constructed so as to be light, strong and durable, it is made of commercial iron, which may be readily obtained and placed in the car.

In the above has been described one embodiment of my invention, and it is obvious that many other embodiments may be made involving one or more features thereof, as it is broadly new to resiliently support a car body between side frames, and this feature may be applied to all kinds of vehicles. This and many other features may be used in other connections, 30 and so I wish it understood that I do not regard my invention as limited to the particular embodiment hereinbefore set forth, but wish it to be understood as being set forth in the following claims:—

1. In a car or similar vehicle, a car body with a side frame attached thereto, and a second frame separate and distinct from said side frame which resiliently supports the said side frame.

35 2. In a car or similar vehicle, a car body, side frames, each comprising curved or hog-back bars fixed to said car body, and a car frame resiliently supporting said side frame, so that the relative movement is permitted between said side frames and said car frame.

40 3. In a car or similar vehicle, a car body with a frame fastened thereto, a rectangular frame and a bolster resiliently supported on said rectangular frame and secured to the frame fastened to the car body.

45 4. In a car or similar vehicle, a rectangular frame, a crossing uniting the side sills of said frame, springs supported by said crossing, bolsters resting on said springs, and a car body supported by said bolsters.

50 5. In a car or similar vehicle, a rectangular frame comprising side sills and crossings, springs supported by said crossings, bolsters resting on said springs, and a car body supported by said bolster.

55 6. In a car or similar vehicle, a frame comprising side sills and crossings, guides above said crossings and running parallel therewith, springs supported by said crossings and between said guides, a bolster resting on said springs between said guides, and a car body supported by said bolster.

70 7. In a car or similar vehicle, a frame comprising side sills and crossings, plates resting on said crossings, and having their ends turned upwardly, guides resting on said plates, and running parallel with said crossings, and secured to the upturned ends of said plates, springs supported by said plates, and bolsters supported by said springs, and side frames supported by said bolsters and fixed thereto.

75 8. In a car or similar vehicle, a frame comprising side sills and crossings uniting said sills, plates with upturned ends resting on said crossings, guides fixed to said plates and to the upturned ends thereof, spring caps resting on

said plates, springs on said caps, a second set of caps on said springs, and a car body resiliently supported on said last mentioned spring caps.

9. In a car or similar vehicle, a frame provided with sills, said sills united by a crossing and plates provided with upturned ends, guides fixed to said plates and to the upturned ends thereof, springs supported by said plates, bolsters resting on said springs, and means for securing 80 said bolsters between said guides.

10. In a car or similar vehicle, frame comprising side sills and crossings, plates on said crossings, two of which are provided with upturned ends, guides fixed to said plates and the upturned ends, springs supported by said plates 85 and between said guides, the bolster resting on said springs, straps for securing same between said guides, and side frames secured to said bolster.

11. In a car or similar vehicle, a frame comprising longitudinal sills connected by crossings, means for resiliently supporting bolsters on said frame, means for securing 90 a car body to said bolsters, and a car body secured to said securing means.

12. In a car or similar vehicle, a frame comprising longitudinal sills connected by crossings, a car bolster resiliently supported by said frame and a car body fixed to said bolster, and a longitudinally disposed rib in the bottom of 95 said car body which extends from the bolster.

13. In a car or similar vehicle, a frame, means for supporting a car body resiliently from said frame, and a car 100 body with a longitudinal rib or brace secured to said supporting means.

14. In a car or similar vehicle, a frame, a car body provided with a longitudinally disposed brace extending along its bottom, and means for resiliently supporting 105 said car body on said frame.

15. In a car or similar vehicle, a car frame, side frames adapted to support a car body between them, and means for resiliently supporting said side frames on said car frame.

16. In a car or similar vehicle, a car frame, a car body, side frames fixed to each side of said car body, and means for resiliently supporting said side frames and car body upon said frame.

17. In a car or similar vehicle, a frame, springs supported thereby, a bolster supported by said springs, a side frame, a car body, and means fixed to said car body, where by it is supported by said side frame and bolster.

18. In a car or similar vehicle, a frame, a spring supported by said frame, bolsters supported by said springs, 120 triangular tubes secured thereto, side frames secured to said bolster and said triangular tube, and an angle iron also secured to said side frames and said triangular tube.

19. In a car or similar vehicle, a car frame, a car body or hopper, and means for resiliently supporting said hopper removably on said frame.

20. In a car or similar vehicle, a frame, provided with crossings, bracing plates secured to said crossings and channel irons resting on and fixed to said plates.

21. In a car or similar vehicle, a frame, comprising sills with crossings and plates fixed thereto, and channel irons riveted to said plates.

22. In a car or similar vehicle, a frame comprising side sills and crossings, and castings to receive a king bolt fixed to said crossings, plates resting on said sills and 135 crossings, and angle irons fixed to said plates and running parallel to said crossings.

23. A frame for cars and the like comprising side sills, parallel crossings, plates with upwardly turned flanges resting on said crossings and sills and fixed thereto, angle irons resting on said plates, and fixed thereto, and tie-bars fixed to said angle irons.

24. A frame for cars comprising side sills and crossings fixed thereto, plates with upwardly turned flanges fixed to and resting on said sills and crossings, channel irons fixed to said plates, spring caps resting on said plates, bolsters between said channel irons, and resilient means for resting on said spring caps for supporting said bolsters.

25. A frame for cars and the like, comprising side sills, united by crossings, angle plates with upwardly turned flanges resting on said sills and crossings, channel irons fixed to said plates, and a bolster resting between said

- channel irons, and means fixed to said channel irons to prevent the removal of said bolster.
26. A frame for cars and the like, comprising side sills and crossings, angle plates fixed to said sills and crossings, channel irons fixed to said angle plates, springs supported by said plate, a bolster supported by said springs, and tie-bars fixed to said channel irons to prevent the removal of said bolster.
27. In a car frame or similar structure, side sills, crossings uniting said sills, angle plates fixed to said sills and crossings, channel irons resting on said plates, caps also resting on said plates, springs resting on said caps, and a second set of caps on said springs, and a bolster resting on said second set of caps.
- 10 28. In a car frame or similar structure, side sills, crossings uniting said sills, plates resting on said crossings and sills, channel irons connecting said plates and fixed thereto, and a spring supported bolster between said channel irons, said bolster comprising two I-beams with a channel iron resting thereon.
29. In a car frame or similar device, side sills, crossings, and plates above and below said sills and crossings, and fixed thereto, said upper plate being provided with upwardly turned flange or brace.
- 25 30. In a car frame or similar structure, side sills, crossings, plates fixed to said crossings and sills, channel irons resting on some of said plates, and a spring supported bolster between said channel iron and a tube secured to the upper surface of said bolster.
- 30 31. In a car or similar structure, side sills, and crossings, plates fixed to said sills and crossings, and supporting channel irons, a spring supported bolster resting between said channel irons, a recessed tube resting on said bolster, and tie-bars passing between said bolster and tube and fixed to said channel irons, to hold said bolster in place.
32. In a frame for cars and the like, side sills and crossings united by plates, channel irons resting on said plates, a spring supported bolster resting between said channel irons and a tube fixed to said bolster, and a piece of angle metal fixed to said tube.
- 40 33. A frame for cars and the like, comprising side sills, crossings uniting said side sills, plates fixed to said crossings and side sills, channel irons resting on said plates, a spring supported bolster between said channel irons, and a recessed tube fixed to said bolster, an angle bar fixed to said tube, and means passing between said bolster and tube for holding the bolster in place.
- 45 34. In a car frame or similar device, side sills, and crossings, united by plates, channel irons resting on said plates, a spring supported bolster between said channel irons and extending above the same, a tube fixed to the upper surface of said bolster, and means for holding said bolster in position.
- 55 35. In a car or similar device, a frame comprising side sills united by crossings and plates, channel irons resting on said plates, and running parallel with said crossings, a spring supported bolster between said channel irons, a tube fixed to the upper surface of said bolster, and a car body or hopper fixed to said tube.
- 60 36. In a car or similar device, a frame comprising side sills and crossings united by plates, channel irons on said plates, and a spring supported bolster between said channel irons, a tube fixed to the upper surface of said bolster, a hopper or car body fixed to said tube, and braces in said car body adjacent to said bolster.
- 65 37. In a car or similar device, a frame comprising side sills, and crossings united by plates, channel irons running parallel with said crossings and fixed to said plates near each end of the frame, a spring supported bolster between each pair of channel irons, and a secondary frame uniting said bolsters.
- 70 38. In a car or similar device, a frame comprising side sills, united by two pairs of crossings, plates secured to said crossings and sills, two pairs of channel irons secured to said plates and running parallel with said crossings, a spring supported bolster between each pair of channel irons, a tube resting on each bolster, angle bars fixed to each tube, and side frames uniting said bolsters, tubes and angle bars.
- 75 39. A frame for cars and the like, comprising side frames united by tubes and angle irons.
40. A side frame for cars and the like, comprising tubes and angle bars united by curved and straight angle irons.
- 80 41. In a car or the like, the combination with a hopper, of a secondary frame, said secondary frame comprising tubes, angle bars connected by straight and curved angle irons.
- 85 42. In a car or the like, a hopper, with vertical braces in combination with a secondary frame comprising tubes and angle bars connected by curved and straight angle irons, so that said vertical braces and said curved and straight irons strengthen each other.
- 90 43. In a car or similar vehicle, a hopper, provided with vertical braces and a longitudinally extending brace, a secondary frame comprising tubes, and angle bars, united by curved and straight angle irons which are fixed to the hopper and to the said tubes and angle bars.
- Signed at the city, county and State of New York, this 16th day of May, 1903.
